FLOOR LAYING TOOL

Allan C. Leslie, Watrous, Saskatchewan, Canada

Application November 6, 1950, Serial No. 194,211
In Canada November 10, 1949

2 Claims. (Cl. 145—1)

1

This invention relates to a tool for laying wooden flooring of the conventional tongue-and-groove type.

The tool of my invention is designed to serve the dual purpose of driving the grooved side of a floor board tightly against the tongued side of an already-laid board and at the same time impart the final driving action to a nail being used to hold in place the driven board.

When flooring is being laid and a particular board does not easily fit into its desired position flush against the previously laid board, it is customary to lay a protective wooden block against the tongued side of the board, to hammer the block until the board is desirably positioned and then, drive nails through the tongued side of the board at an angle of 45 degrees and at a point along the upper line of inception of the tongue, usually followed by a nail-punching step. This is a somewhat laborious procedure and is unsatisfactory for the additional reason that the board being laid sometimes springs back from its driven position before the holding nails can be completely driven home, and the drawing power of the nails may be insufficient to properly reposition the board.

Certain proposals have been made for floor laying tools which simultaneously drive the nail home and the board inwards, and an example of such a proposal is to be found in Canadian Patent Number 175,962 which issued to A. N. Landgraf on March 27th, 1917. This proposal possesses the serious disadvantage that since the driving side of tool is supported only by upper portions of the board being laid and the device is designed to be hammered upon an anvil head which extends at substantially 45 degrees from the driving side of the tool, the outer edge of the driven board tends to be driven down too far resulting in difficulties in mating the tongue of that board with groove of the next board which is to be laid.

I have overcome this disadvantage by the provision of a handled floor laying tool having a body portion which is of generally square vertical cross-section and of an elongated rectangular horizontal cross-section, said body portion having a horizontal groove formed in and extending along the complete length of one longitudinal side thereof, said body portion being of a height which is substantially equal to that of the flooring board it is designed to drive, said groove being complementary in shape to the tongue of said flooring board and disposed the same distance from the base of said body portion as said tongue is disposed from the base of said flooring board.

2

The nature of my invention will be more clearly understood after a study of the detailed specification which follows and the accompanying drawings. In the drawings:

5 Figure 1 is a perspective view of one embodiment of a floor laying tool in accordance with my invention.

10 Figure 2 is an exploded perspective view of another embodiment having a foot plate, a removable body portion, and a removable handle, and

15 Figure 3 is a perspective view of the lower portions of the removable handle employed with the embodiment shown in Figure 2.

20 Reference numeral 10 generally indicates the body portion of a floor laying tool having a handle 11. Body portion 10 has a generally square vertical cross-section and an elongated rectangular horizontal cross-section. Handle 11 extends upwardly and laterally from the upper surface of rectangular body 10, and is secured thereto by welding or equivalent means as indicated at 12 in the drawing. A horizontal groove 13 is formed in, and extends along the complete length 25 of one longitudinal side of body portion 10, and is disposed in the side of the body portion over which handle 11 extends. A second horizontal groove 14, similar to the groove 13, extends along one of the short sides of rectangular block 10.

30 Flooring boards are sold in standardized sizes of overall cross-sectioned dimensions and size and disposition of tongues and grooves. It is my intention that floor laying tools according to my invention be made available in sizes which correspond to these standardized board sizes in the following particulars. The height of rectangular body portion 10 is to be substantially the height of the flooring boards it is designed to drive, and the grooves 13 and 14 are to be complementary in shape to the tongue of said flooring boards and disposed the same distance from the base of the body portion as the tongues of said flooring boards are disposed from the bases thereof.

35 40 45 The floor laying tool of my invention is preferably constructed entirely of a metal such as steel.

Having described the physical characteristics of one embodiment of a floor laying tool according to my invention, I will now set out the best methods known to me for utilizing this embodiment. Body portion 10 is held against the outer side of the board which is being laid, with groove 13 mating with the tongue of the board. The board is then driven towards the desired flush 50 55 union with a previously laid board by hammering

upon the non-grooved or outer side of the body portion 10. A flooring nail is then driven through the board in the conventional manner and at the conventional position i. e. at an angle of about 45 degrees and at a point along the upper line of inception of the tongue. When the nail has been driven nearly completely home in this conventional manner, the floor laying tool is re-applied to the board, this time over an area which includes the nearly-driven nail. The outer edge of the tool is then hammered again whereby the board is driven inward and nail is driven further inward and downward to hold the board in its driven position. (It will be appreciated that the nearly-driven nail is necessarily driven since when the tool is applied as described the nail head will rest against the flat portion which extends above the groove 13.) Since the board and nail are driven simultaneously there is no danger of the board springing back, and since the board is solidly supported by that portion of the body 10 which extends below the tongue of the board, there can be no danger that outer edge of the board will be driven downwardly too far and cause difficulty of union with the next board to be laid.

While groove 14 is not an essential element of the floor laying tool of my invention, I preferably provide such a groove since it somewhat extends the usefulness of the device. When flooring is being laid close to a wall it may not be possible to employ the device shown in Figure 2 in the fashion described above due to the length of the handle 11 (which may be obstructed by the wall). If such is the case, the tool may be turned through 90 degrees and groove 14 employed in the same general manner as described in connection with groove 13.

Reference will now be made to the embodiment shown in Figures 2 and 3, which differs from the embodiment shown in Figure 1 mainly in that it includes a foot plate, and that the body portion is detachable, and the handle is removable and hinged with respect to the body portion. Body portion 10a in Figure 2 is generally similar to body portion 10 in Figure 1 and is provided with similar horizontal grooves 13 (along one longitudinal side) and 14 (along one of the short sides). Two threaded holes, one of which may be noted at 15 in Figure 2, extend vertically downward from the upper surface of body portion 10a. A foot plate 16, having a raised portion 17 for the reception of the handle, and a hammering surface 18, is provided with two circular holes 19 which extend through the plate and are spaced apart the same distance as the threaded holes 15 in body portion 10a. Threaded bolts 20, having split ring washers 21, may be passed through the holes 19 and threadedly engaged in the holes 15 to rigidly secure the foot plate 16 and the body portion 10a to one another. When the foot plate is thus secured to the body portion, the flat foot receiving portion of the plate extends centrally and laterally from the side of the body portion having the groove 13.

A single length of metallic rod is bent to form a handle 11a of elongated U-shaped form. The ends of the rod forming the handle are bent, first outwardly through substantially 45 degrees, and then inwardly through substantially 135 degrees, to form two axially aligned mounting studs 22. Axially aligned cylindrical recesses having diameters slightly greater than the diameter of the studs 22 are provided in opposed

sides of raised portion 17. The bending of the rod to the elongated U-shape is such that the ends of the mounting studs 22 are spring urged to occupy a distance apart from one another which is approximately equal to the distance between the inner ends of the recesses in the raised portion 17. The arms of handle 11a may however be spread apart against this spring action a sufficient distance to enable the ends of the mounting studs to clear the sides of raised portion 17 during the mounting of the handle on the tool or its removal therefrom.

It will be appreciated that the mounting of the handle 11a by the insertion of the studs 22 in the recesses in raised portion 17 gives a hinged connection. Hinging of the handle not only avoids the problem of wall obstruction described above, but, if a handle 11a of sufficient length is used the operator is able to effectively employ the tool when in a standing position.

I envisage that a complete tool kit associated with the floor laying tool according to my invention will include a plurality of the handles 11a of varying length so that the user may select the length he finds most convenient in performing a particular floor laying task. Moreover, I propose to also include in the kit a plurality of body portions 10a of different depths and different groove specifications corresponding to the several standardized flooring thicknesses and tongue specifications commonly encountered.

The embodiment shown in Figures 2 and 3 is used in much the same fashion as the embodiment shown in Figure 1, and since the use of the latter has already been described, a full description of the use of the former appears to be unnecessary. The only differences in usage are that the second embodiment may be foot-held in any desired position due to the provision of the foot plate 16, the board is forced into position and the nails driven home by hammering upon the surface 18 rather than directly upon the outer or non-grooved side of the body portion, and, as already pointed out, the hinging of the handle 11a makes the second embodiment more convenient.

What I claim as my invention is:

1. A floor laying tool comprising a body portion and a handle portion, said body portion being of generally square vertical cross-section and of an elongated rectangular horizontal cross-section, said body portion having a horizontal groove formed in and extending along the complete length of one longitudinal side thereof, said body portion being of a height substantially corresponding to that of the flooring board it is designed to drive, said groove being complementary in shape to the tongue of said flooring board and disposed the same distance from the base of said body portion as said tongue is disposed from the base of said flooring board, said body portion being detachably connected to a foot plate, and said handle being detachably hingedly connected to said foot plate.

2. A floor laying tool comprising a body portion and a handle portion, said body portion being of generally square vertical cross-section and of an elongated rectangular horizontal cross-section, said body portion having a horizontal groove formed in and extending along the complete length of one longitudinal side thereof, said body portion being of a height substantially corresponding to that of the flooring board it is designed to drive, said groove being complementary in shape to the tongue of said flooring board and

disposed the same distance from the base of said body portion as said tongue is disposed from the base of said flooring board, said body portion being detachably connected to a foot plate, said handle being detachably hingedly connected to said foot plate, said foot plate including a raised portion having axially aligned cylindrical recesses in its sides, said recesses being substantially parallel to the longitudinal axis of the body portion, said handle being a metallic rod centrally bent to the form of an elongated U, the ends of said rod being bent first outwardly and then inwardly to form two axially aligned mounting studs, said handle being hingedly connected

to said foot plate by the insertion of said studs in said recesses.
